UNITED STATES PATENT OFFICE.

GEORGE FUSSELL, OF LOCKPORT, NEW YORK.

MEANS FOR NITRATING GUNCOTTON.

1,296,280.

Specification of Letters Patent.

Patented Mar. 4, 1919.

Application filed March 1, 1917. Serial No. 151,772.

To all whom it may concern:

Be it known that I, GEORGE FUSSELL, a citizen of the United States of America, residing at Lockport, in the county of Niagara 5 and State of New York, have invented certain new and useful Improvements in Means for Nitrating Guncotton, of which the following is a specification.

This invention relates to improvements in 10 means for nitrating gun cotton, and more particularly to the means for wringing the cotton to remove excess acid.

In nitrating gun cotton, considerable difficulty is experienced in preventing the cotton catching fire after the excess acid is extracted, and while still in the nitrating apparatus. This occurs largely because of the heat, due to friction, in the treatment of the 15 cotton and the combustible nature of the product. The excessive heat causes spontaneous combustion, and the practically dried nitrated cotton is destroyed, resulting in great loss of material and machinery, and considerable delay.

20 The objects of this invention are to provide a wringer for expelling excess acid from the gun cotton, separating the acid from the treated cotton, and separating the fumes and carrying same off, the parts being so arranged that the cotton is simultaneously, centrifugally, spirally, and vertically kept in motion, and is to a considerable extent disintegrated to prevent liability of spontaneous combustion.

25 A further object of the invention is to provide means for preventing the cotton forming wads and sticking while the wringing operation is progressing.

30 A still further object of the invention is to provide means for subjecting the cotton to a water bath after the excess acid is removed to cool it and partially wash it.

35 A still further object of the invention is to provide means for regulating the period of time the cotton is subjected to the wringing operation.

The invention also comprehends improvements in the details of construction and arrangement of parts which will be herein-after described and particularly pointed out in the claims.

In the drawings:

Figure 1 is a central vertical section of my improved wringer.

40 Fig. 2 is a horizontal section on the line 2-2, of Fig. 1.

Fig. 3 is a detail horizontal section on the line 3-3, of Fig. 1.

Fig. 4 is a side view of the feed screw.

The numeral 1, indicates a circular stationary casing, provided at its lower end with an annular gutter 2, and communicating with the bottom thereof is an acid drain pipe 3, formed with a trap 4. Supported on top of the casing 1, is the flange 5, of an annular perforated basket 6, which tapers downwardly and terminates within the inner end of the gutter 2. The basket is spaced from the walls of the casing 1, to form an annular passage 7, for the acid expelled through the perforations 6^a, the acid dropping into and is trapped in the gutter 2, and is carried off through the drain pipe 3, the trapped acid forming a seal to prevent the fumes escaping.

75 The bottom plate 8, of the basket fits over the upper inner walls of the gutter 2, to form a seal, and to the center of the bottom plate 8, and extending above and below the same is a hollow shaft 9, through which extends a vertical shaft 10. To the upper end of the shaft 10, is secured the hub of a spider 11, the outer ends of the latter being bolted to the inner surface of a cone-shape hollow hub 12, of a screw 13. The lower 80 edge of the hub 12, is cut away to form an exit opening 14, and adjacent the cut away portion a flat spiral thread 15, commences. The flat spiral thread continues to a point 85 near the top of the cone shape hub, and terminates substantially on a level with the upper flange 5, of the basket 6. The walls of the casing, and the walls of the cone incline in opposite directions, forming a restricted 90 space at the bottom, and a wide exit at the top, the thread gradually increasing in width as it approaches the upper end, the purpose of which will be hereinafter set forth.

95 Depending from the top of the outside of the casing 1, is a gutter 16, and communicating therewith is a draw-off flue 17, provided with a trap 18, and diametrically opposite thereto is a vent pipe 20, which also communicates with the gutter 16, above the normal water level maintained by the trap 18. This pipe extends downwardly to convey the fumes away from the apparatus, as shown. Extending from the pipe 20, is a 100 branch pipe 22, which communicates with the lower gutter 2, to convey the fumes therefrom.

A water supply pipe 23, communicates with the upper gutter, and is provided with two oppositely disposed nozzles 24, to supply currents of water in two directions toward the draw-off flue 17.

5 The outer wall of the upper gutter extends up beyond the top of the basket, and is provided with a cover plate 25, a space 24*, being thus formed between the plate and the 10 top of the basket, through which the nitrated cotton is thrown by the screw thread 15.

To the top of the cone-shape hub 12, is attached a flange 24^a, which snugly fits in an 15 opening formed in the plate 25, and depending from this flange is a feed chute 25^a, the latter extending down into the cone-shape hub, and through, and below the spider 11, therein. Bolted to the flange 24^a, is an upper flange 26, and extending therefrom is a 20 section 26^a of a feed chute, arranged in alignment with, and forms a continuation of the chute section 25^a. The upper end of the feed chute section 26^a, is mounted in a bearing 28, and turns therein, as will presently appear.

25 To the lower end of the vertical shaft 10 is fixed a pinion 30, and to the lower end of the hollow shaft 9, is fixed a similar pinion 31, one of said pinions being smaller than the 30 other to rotate the basket and the screw at different speeds. Adjacent the shaft 10, is a driven shaft 32, and a driving shaft 33. To the driving shaft is secured a gear wheel 34, which meshes with the pinion 30 on the 35 vertical shaft 10, and to the driven shaft 32, is secured a gear wheel 34^a, which meshes with the pinion 31, on the hollow shaft 9. On the driving shaft 33, is attached the female member 35, of a clutch, and to the 40 driven shaft is attached the male member 36, the latter being held in position by the usual spring, and is actuated to disconnect the clutch by a lever 36^a. To the lever 36^a, is pivoted a link 37, the upper end being secured to a brake 38, shown acting on the 45 pinion 31.

The gearing and the clutch just described are shown conventionally, it being understood that any well known mechanism may 50 be employed.

In operation, power is applied to the driving shaft 33, and through the gearing and the clutch the basket and the screw are rapidly rotated. Gun cotton, saturated with 55 acid, is fed to the open end of the feed chute, and is delivered to the lower portion of the interior of the cone-shape hub 12, below the spider 11, and it falls on the bottom plate 8, of the basket. At this point it may be emphasized that it is important that the entire 60 construction forming the walls of the passages be as free from projections and uneven surfaces as possible, to prevent the cotton accumulating and eventually forming 65 wads. It is primarily for this purpose that

the feed chute is extended as shown, to insure of the delivery of the cotton to the rapidly rotating plate 8.

The saturated cotton is delivered to the bottom plate 8, and by centrifugal force it is 70 thrown out with great force through the outlet opening 14, and against the perforated wall of the basket. The cotton is now caught by the rapidly moving screw thread 15, and is spirally elevated and centrifugally thrown 75 out against the perforated walls of the basket. These various movements imparted to the cotton all serve to continuously and alternately disintegrate the fibers, and centrifugally throw the mass against the 80 perforated wall and expel the acid, and dry the cotton. The cotton tends to cling close to the walls of the basket, and with the air introduced through the feed chute, and the agitation of the air by the screw thread 85 serves additionally to dry the cotton and force the acid and fumes therefrom.

The hub and its thread are rotated at a high rate of speed; so also is the basket, but the latter is rotated at a slower speed, the 90 relative difference in the speed determining the length of time it takes cotton to travel from the plate 8, to the upper end of the basket.

I have found this difference in speed can 95 be regulated so that the cotton can be caused to travel faster or slower from the bottom to the top of the screw, and at the same time obtain the necessary velocity to create the required centrifugal force to expel the acid 100 from the cotton.

To illustrate the principle of operation involved, let it be assumed that the basket and the screw are rotated at the same speed, and cotton has been introduced to the thread. 105 Under such circumstances the cotton remains in fixed relation between the screw and the basket no matter how fast they be revolved.

As a further illustration, let it be assumed that the cotton be introduced to the thread, 110 and the basket is held stationary, and the screw be rapidly rotated. Under these circumstances the cotton would be quickly elevated from the bottom plate 8, to the top of the basket, the rapidity of its movement upwardly being only a question of the pitch of the screw, and the number of revolutions imparted per minute. Obviously, if the screw be rapidly rotated, the cotton would be so quickly elevated from the plate to the 115 top of the basket that sufficient time would not be allowed for drying and expelling the acid.

Now, according to my invention, I approximate that the speed of the screw 120 should be about 1800 revolutions per minute, and that it requires about three minutes from the time the cotton is introduced to the plate 8 until it reaches the top of the basket, to expel the excess acid, and dry the 130

cotton. To accomplish this important function, and at the same time obtain the necessary centrifugal force, the number of revolutions per minute of the basket is less than 5 the number of revolutions per minute of the screw, the basket and the screw, however, rotating in the same direction. Considering the previously cited illustrations, it will be seen that by this difference in movement, 10 the necessary centrifugal action of the cotton is obtained, and at the same time the cotton in transit is retained within the wringer the required time to expel the excess acid, the duration of the treatment being 15 determined altogether by the relative speed of the two parts. This difference in movement of the two elements, between which the cotton is confined, is of the utmost importance, in that the high speed, and the necessary time required to wring the cotton 20 is under perfect control.

In gun cotton wringers where the cotton is centrifugally thrown against the perforated walls of a container or basket, the 25 cotton packs, and separate mechanism, or a separate operation is required to remove it after treatment. With my construction this condition is absent.

Because of the gradually increasing space 30 between the hub, basket, and screw, the cotton tends to spread as the space in which it is confined is constantly changing, and because of the various movements imparted to it, packing is effectually avoided.

35 When the cotton reaches the upper end of the screw, it is thrown centrifugally over the top of the basket through space 23*, and against the outer walls of the upper gutter and falls into the gutter 16, where it 40 is subjected to a partial washing. Water is continuously introduced into the gutter through the pipe 20, and because of the location of the nozzles 24, the water flows in two opposite directions toward the outlet 45 flue 17, and carries the treated cotton off.

The fumes from the saturated cotton rise to the top of the basket, and are carried off through the pipe 20, the water seal in the trap 18, preventing the fumes passing 50 through the flue 17. The fumes from the acid expelled from the cotton in the space 7, and the acid in the gutter 2, are carried off through the branch pipe 22, while the excess acid in the gutter 2, is carried off 55 through the drain pipe 3, the bottom of the gutter inclining sufficiently to cause the flow of liquid toward the pipe.

When the cotton reaches the top of the screw, it is thrown into a space of such area 60 that it separates, and, as stated, is carried off without stopping the wringing operation, a feature which I regard as of considerable importance, when it is considered that at present it is customary to remove the 65 treated cotton by a separate operation.

The rapidity of movement of the cotton, and the friction it is subjected to by contact with the interior surface of the wringer soon dries it, and unless means are provided for moving it when it becomes unusually 70 dry, it ignites, which entails considerable loss. While under normal conditions the construction described will keep the cotton moving, and will cause it to disintegrate sufficiently to prevent this undue heat. Yet 75 there may be a time when the cotton will ignite, and with my construction the fire can be extinguished. For instance, let it be supposed that the cotton near the top of the basket should ignite, the point where 80 fire usually occurs, the hand lever 36* is depressed, and the clutch member 36 is released, and at the same time the brake 38, is caused to engage the gear wheel 31, consequently the speed of the basket is either 85 reduced or stopped. The result is the cotton on the screw is caused to travel faster to the top of the basket and that which is ignited is quickly thrown into the water in the gutter 16. When the basket is stopped, the 90 screw moves the cotton toward the top so rapidly that the ignited cotton cannot carry the fire to the mass of cotton below. By this means, when the ignited cotton is delivered to the water, the clutch is again 95 engaged, and the wringer operates as before described.

In the rotation of the screw the feeding tube is correspondingly rotated, the saturated cotton being forced or otherwise introduced to the tube.

My invention is not limited to nitrating cotton as it is evident that for dehydrating cotton it is only necessary to introduce the previously treated cotton through the feed 100 chute, the alcohol being forced through the perforations in the basket, exactly the same as when expelling the acid.

If it is desired to use the apparatus for steaming, cotton and steam are introduced 110 to the basket through the feed chute, the condensed steam being carried off like in the case of acid. When using the apparatus for dehydrating, or steaming cotton, the water is removed from the trough 16, and 115 air is blown through the nozzles, or any other conveying means may be employed to carry the treated cotton from the gutter.

From the foregoing description it will be seen that I have provided a machine for 120 expelling excess acid from gun cotton, without liability of choking, and one where the cotton after treatment is conveyed from the wringer without stopping the apparatus.

By the arrangement described, the acid, 125 fumes, and dried cotton, are effectually separated, and ample provision is provided for preventing the escape of the fumes.

What I claim is:

1. In an apparatus of the class described, 130

the combination of a casing provided at its bottom with a continuous acid receiving gutter, a perforated basket rotatably mounted in the casing above the acid receiving gutter and spaced from the walls of the casing, a rotatably mounted hollow screw in the basket, one edge of the hollow screw below the thread being cut away to form an opening for the passage of cotton, the lower edge 10 of the screw thread engaging the bottom of the basket, means for feeding saturated cotton to the interior of the screw, means inclosed within the casing and below the top of the basket for receiving and conveying 15 the treated cotton from the top of the screw, and means for rotating the screw and basket at different speeds.

2. In an apparatus of the class described, the combination of a casing, a perforated 20 basket rotatably mounted in the casing and spaced from the walls of the latter, a hollow screw rotatably mounted in the basket, one side of the lower edge of the screw being cut away to form an opening below the 25 thread, the lower edge of the thread engaging the bottom of the basket, means for rotating the basket and the screw at different speeds and in the same direction, means for introducing saturated cotton through the 30 screw to the opening therein to the bottom of the basket, a cotton receiving chamber surrounding the upper portion of the casing, and means for conveying the treated cotton from the receiving chamber.

3. In a machine of the class described, the combination of an inclosing casing provided at its bottom with an inclosed acid receiving gutter, and at its top with an inclosed cotton receiving chamber, means for 40 introducing water to the cotton receiving chamber, a perforated basket inclosed within and spaced from the side walls of the casing, a hollow screw mounted within the basket, means for rotating the basket and 45 the screw at different speeds, means for introducing saturated gun cotton through one side of the bottom of the screw to the bottom of the basket, and means for conveying the acid fumes from the cotton receiving 50 chamber and the gutter.

4. In a machine of the class described, the combination of a casing, a perforated basket mounted in the casing, a hollow hub formed on its periphery with a spiral thread and 55 formed at one edge of the bottom with an opening to communicate with the basket for introducing cotton to the bottom of the latter, means for introducing saturated cotton into the hollow hub, a cotton receiving chamber above the screw, and a gutter having water therein below the top of the chamber.

5. In an apparatus of the class described, the combination of a casing, a rotary perforated basket in the casing, means in the basket for elevating the cotton when cen-

trifugally thrown by the movement of the basket, a cotton receiving chamber above the basket, and a gutter at the bottom of the chamber provided with water into which the treated cotton falls.

6. In an apparatus of the class described, the combination of a casing, a perforated basket in the casing, means for rotating the basket, and means cooperating with the basket for elevating the cotton, said means 70 engaging the bottom of the basket and formed with an outlet opening adjacent the point of engagement of said means with the bottom of the basket, inclosed means surrounding the casing for receiving the treated 75 cotton, and an inclosed annular gutter in the bottom of the casing outside the basket for receiving the acid expelled from the cotton.

7. In an apparatus of the class described, the combination of a casing, a rotatable basket therein having downwardly tapered perforated walls, hollow rotatable means operating in the basket to elevate the treated 80 cotton, means for rotating the basket and the 85 rotatable means therein, a chute extending through and rotatable with the hollow rotatable means for introducing cotton to the bottom of the basket, an inclosed annular chamber outside the top part of the casing 90 into which the treated cotton is thrown, and a gutter below the basket for receiving the liquid expelled from the cotton.

8. In a machine of the class described the combination of a hollow rotatable screw 100 formed with an exit at its bottom, a feed chute extending through the hollow screw and rotatable therewith, a perforated basket in which the screw operates, a cotton receiving chamber adjacent the top of the basket, 105 a gutter in the bottom of the latter, an exit flue connected to the gutter, means for supplying a moving stream of water in the gutter, a gutter at the bottom of the casing 110 to receive the liquid expelled from the cotton, and means communicating with the two gutters for carrying off fumes.

9. In a machine of the class described, the combination of an inclosing casing provided at its bottom with an inclosed annular gutter, 115 and at its upper end below the top with an inclosed annular gutter, a perforated basket having a flange at its upper end and a flange at its lower end, the upper flange extending over the upper end of the casing and the lower flange extending down into the lower gutter, the sides of the basket being spaced from the casing, a hollow shaft extending from the basket, a shaft extending through the hollow shaft and supporting a hollow 120 screw the thread of which varies in width, the bottom of the screw being cut away on one side below the thread to form an exit for cotton, a feed chute extending into the screw, the screw elevating the treated cotton 125

while centrifugally thrown by the basket, the treated cotton being thrown into the gutter at the top of the casing, means for conveying the cotton from said gutter, and means 5 for conveying the expelled liquid from the lower gutter.

10. In a machine of the class described, the combination with an inclosing casing, a perforated basket spaced from the top of the casing, said space forming a chamber, means in the basket for continuously raising the cotton from the bottom to the top of the basket from whence the treated cotton is centrifugally thrown into the chamber, means 15 extending through the cotton raising means for introducing cotton to the bottom of the basket, and an inclosed gutter surrounding the bottom of the inclosing casing for carrying off the liquid expelled from the cotton.
20. 11. In a machine of the class described, the combination of a casing, a basket mounted in and spaced from the walls of the casing, a rotatable screw mounted in the casing, a chute extending through and rotatable 25 with the screw for introducing saturated cotton to the bottom of the basket, an inclosed chamber at the top of the casing into which the treated cotton is delivered, means for conveying the cotton from the chamber, 30 an inclosed gutter surrounding the bottom of the casing to receive the liquid expelled from the cotton, and a flue in which a forced draft is created to draw the fumes from the 35 chamber and the gutter.
12. In a machine of the class described, the combination of a casing, a perforated

basket mounted in and spaced from the casing, a hollow screw mounted in the casing and provided at its lower end below the 40 screw thread with a cut-away portion to form an exit for cotton, a bearing above the casing, a feed chute extending from the top of the screw and mounted in the bearing, said chute extending down into the screw, a 45 bearing at the bottom of the screw, a shaft mounted in the latter bearing, means for rotating the shaft, means for rotating the bearing, an inclosed chamber at the top of the casing to receive the cotton thrown out of 50 the basket, and an inclosed gutter below the casing for conveying the liquid expelled from the cotton.

13. In an apparatus of the class described comprising an inclosing casing provided at 55 its upper end with an inclosed gutter and at its lower end with an inclosed gutter, a basket mounted in the casing and snugly embracing the inner upper edge of the lower gutter, a duct connecting with the two gutters to carry off the fumes, a hollow screw mounted in the basket and provided with an exit at its bottom, means for introducing 60 cotton through the exit to the bottom of the basket, and means for rotating the basket 65 and the hollow screw in the same direction and at different speeds.

In testimony whereof I affix my signature in the presence of two witnesses.

GEORGE FUSSELL.
